UNITED STATES PATENT OFFICE.

CHARLES C. SPENGLER, OF ROCKFORD, ILLINOIS, ASSIGNOR TO SPENGLER-LOOMIS MANUFACTURING CO., OF CHICAGO, ILLINOIS, A CORPORATION OF NEW YORK.

PENCIL HOLDER FOR SHARPENERS.

Application filed August 20, 1926. Serial No. 130,397.

This invention relates to pencil holding devices employed in connection with pencil sharpeners.

Heretofore in pencil sharpeners of this general type, it has been the practice to provide gripping jaws which are controlled manually for holding the pencil; that is, by positive actuation employing levers or similar elements. This necessitated complicated construction and further, the necessity of unhandy manipulation on the part of the operator.

It is the object of my invention to provide a simple and effective gripping means for holding a pencil while it is being fed into the cutting devices in the process of sharpening the same.

Another object is to eliminate the manual control feature and provide a set of gripping jaws which are actuated by the inserted pencil and which operate effectively entirely by the engagement with the end of the pencil when the pencil is thrust into the holding device.

Another object is to provide a set of gripping jaws for a pencil holder which will always maintain the pencil centered regardless of the size of the pencil and thus present the end portion in a proper position to be engaged by the cutting blades.

Objects of my invention are accomplished preferably by the structures disclosed in the accompanying drawings, in which like reference characters represent corresponding parts, and in which—

Figure 1 is a side elevation showing a manually operated pencil sharpener, comprising a casing containing the cutting apparatus and automatic holding and feeding device;

Figure 2 is a side elevation, partly in cross-section, showing the holding and feeding mechanism, the internal construction being shown in dotted lines;

Figure 3 is a cross-sectional view taken on line 3^x—3^x of Figure 2;

Figure 4 is a detail showing, partly in cross-section, taken on line 4^x—4^x of Figure 1;

Figure 5 is a side elevation of a sharpener similar to that shown in Figure 1 with a stationary casing for the gripping jaws, the automatic feed being dispensed with;

Figure 6 is an end elevation of the form shown in Figure 5 as seen from the left;

Figure 7 is a cross-sectional view of the holding mechanism taken on line 7^x—7^x of Figure 5;

Figure 8 is a cross-sectional view of Figure 7 taken on line 8^x—8^x; and

Figure 9 is a view similar to Figure 8 but showing the inner member of the holder made of a stamping of sheet metal instead of being cast.

Referring to the drawings, 1 represents a base plate; 2 indicates generally a conventional type of sharpening mechanism containing cutting blades and having a handle 3 for manual operation. In the form shown in Figures 1 to 4 inclusive, which embodies an automatic feed, the base plate 1 is provided with an upturned end 5 forming a support for a tubular extension 6 and the outer end of supporting rod 7, which rod is shown in Figure 2 disposed centrally within the tube 6. The tube 6 forms a sliding bearing support for the cylindrical member 8 which together with the rod 7 and the depending arm 9, the end of which is adapted to slide in a slot 11, form a carriage for the feeding mechanism designated generally at 10. Elements 6 and 7 are telescopically arranged and are adapted to contain a coiled spring 12 which exerts a force tending to hold the feeding mechanism in the right hand position shown in Figure 1. The carriage is held in assembled relation by the rod 7 which is inserted from the left, as shown in Figure 1, and is held by screw-threaded engagement with the adjacent end of the casing of the cutting mechanism.

In the form shown in Figures 5 to 9 inclusive, the automatic feed has been dispensed with, the holder being mounted directly on the housing of the cutter, and the feeding of the pencil is accomplished by manual thrust applied by the operator to cause the pencil to slip through the jaws.

All of the features of my invention are the same, however, whether applied with or without the automatic feed, the only difference residing in the positioning of the holder relative to the cutter casing, the eccentric pencil opening being at the side when applied with the automatic type and at the top in the other modification.

The cutter housing may be made in several ways as shown in the various figures, Figure 3 showing a cast frame member for the parts with a disc plate closing the assembly. In Figures 7 and 8, a cast frame is likewise shown but having a cover which completely encloses same thereby eliminating the neces-

sity of polishing the sides of the casting, the cover in this instance being made of stamped metal. In Figure 9, the arrangement is similar to Figure 8 but the frame member is also 5 of stamped metal and is entirely enclosed by a stamped metal cover plate.

My invention relates especially to the holding device which is shown in detail in Figures 3 and 4, 7 and 8, and 9, and which will now be 10 described. Two cooperating members 13 and 14 which may be made in any of the above described forms, constitute a casing which contains the holding mechanism. These parts are held together with suitable screws 15 and 15 are provided with perforations therethrough in alignment with the receiving opening in the casing for the cutting mechanism. This permits a pencil when inserted between the jaws to be properly fed into the sharpener 20 upon movement of the carriage to the right in the automatic feed type or to permit the pencil to slip when thrust into engagement in the other type. Disposed within the casing portion 14, ribs 16 are provided which 25 form a guideway for sliding jaws 17. The jaws provided in the invention as shown are each made of a single piece of metal bent to form a receiving funnel into which the pencil is placed and by which it is guided into 30 aligned relation with the cutting blade. The other end of the jaw members form rectangular plates 26 which constitute slide blocks vertically movable in the guideway provided by ribs 16. The jaws are normally 35 held closed by spring 18 through the action of levers 19 and 20 which bear on the small horizontal bearing surfaces 21 of the jaw members, and the expanding effort of the spring acts in opposite directions, all of which 40 causes the jaws to approach each other. Levers 19 and 20 are preferably formed with offset arms 22 and 23 which are adapted to cooperate with sliding engagement whereby simultaneous movement of equal amount is as- 45 sured thus providing yielding means for the jaws but maintaining the center of the funnel always in proper alignment. The cooperative engagement is accomplished preferably by providing a rounded end 24 and an 50 elongated slot 25 such as shown in Figure 4. The ends of the levers are provided with enlarged heads which have a dual function; first, to engage by edge contact the bearing portion 21 of the jaws, and secondly, to engage 55 with relatively large surface contact on opposite sides of the guide blocks the jaw elements and the inner surface of the casing element 13 so as to completely fill the space between these surfaces in the casing and thereby prevent any tilting of the guide plates 60 causing the jaws to always maintain a proper position and eliminating all tendency to bind in their movement.

This last feature is of great importance 65 inasmuch as the spreading of the jaws is

accomplished by a horizontal thrust of the pencil acting on the inclined sides of the funnel and the components of force which tend to tilt the guide blocks out of position must be restrained to insure proper operation. Adjacent edges of the two portions of the jaws which form the receiving funnel are each provided with rounded protrusions 70 25' which by engagement maintain the jaws when in their closed position sufficiently 75 spaced to permit a pencil to be inserted and to contact the inclined sides of the funnel.

To operate the automatic feed type, the operator grasps the casing 10 of the feeding mechanism in any convenient manner and 80 moves the same to the left against the tension of the spring 12, as shown in Figure 1. The pencil is then inserted into the funnel-shaped extension of the jaws where it causes by 85 wedging action the jaws to spread an amount sufficient to allow the pencil to pass and approach the casing 2, in position to be engaged by the cutting blade. When this is done, the pencil is firmly held in position by the action of the spring 18 and levers 19 90 and 20 and then the spring 12 exerts its force through the carriage and gripping jaws to the pencil to cause the pencil to be fed against the blades in the proper method.

To operate the type disclosed in Figures 95 5 to 9 inclusive, the operator merely thrusts the pencil in the funnel receiving members and between the jaws, the jaws acting to maintain the pencil in proper alignment to contact the cutting blades. During the cutting 100 operation, the operator continues to thrust the pencil inwardly causing the pencil to slip in the jaws at the rate permitted by the removal of material by the cutting process.

It is my intention to cover all modifications of the invention falling within the spirit and scope of the following claims.

I claim:

1. In a pencil holding device, a casing 110 comprising two cooperating members having perforations therethrough adapted to be aligned with a cutting tool, one of said members having two ribs on its inner surface forming a guideway, means forming gripping jaws mounted to slide in said guideway, two levers mounted in said casing and provided with interengaging means, an expanding spring having its opposite ends seated against adjacent ends of the two 115 levers, and the opposite ends of the levers having large flatheads thereon which engage the jaws to yieldingly resist separation of the same and to act as filler means to cause the jaws to maintain a proper vertical position.

2. In a pencil sharpener, a casing composed of two cooperating members, a plurality of jaw elements therein angular in shape to form a vertical part and a horizontal bearing part and a flared receiving 130

part, said jaws being adapted to be moved in a guideway simultaneously in opposite directions, levers mounted in said casing having interengaging arms so that movement of one 5 will cause an equal and opposite movement of the other, a spring interposed between one pair of arms of the levers and the opposite arms having flattened heads thereon adapted to engage edgewise with the horizontal bearing portion and by side contact with a relatively large area of the vertical portion of the jaw elements.

3. A pencil holding device for a pencil sharpener comprising a casing, an opening therethrough, jaw elements mounted in said casing and having portions extending through the opening and movable in opposite directions against spring tension, said jaw elements being made angular shape to form with 10 one part of each a receiving funnel and with the other part of each, sliding elements, said sliding elements being mounted in a guideway and cooperating with levers so that both parts under the control of the levers will recede automatically an equal amount, when a pencil is inserted so as to maintain the center 15 of the opening between the jaws always the same.

4. In a pencil holder, gripping jaws comprising two cooperating angle members yieldingly held together by a spring, one arm of the angle member forming a slide adapted to be held against binding upon movement by engagement with large side bearing surfaces, 20 the other arms cooperating to form a funnel receiving member for a pencil which is adapted, upon insertion of a pencil, to force the jaws apart and protrusions on the angle members which initially hold the jaws apart a 25 predetermined amount.

5. In a pencil sharpener, cutting apparatus, means for holding a pencil comprising a casing, pencil gripping jaws mounted there-

in adapted to slide against spring pressure and presenting outturned extensions with inclined faces, said inclined faces being adapted to engage the end of the pencil when the same is inserted and to cause the jaws to separate to receive same.

6. In a work holding device, a support, a casing on said support, jaws slidably mounted in said casing adapted to yield against spring pressure and having outturned extensions forming a funnel for receiving the work, said jaws being separated to permit the work to be 55 inserted upon application of pressure on the work when same is placed so as to contact the inside faces of the receiving funnel.

7. In a pencil sharpener, a pencil holding means comprising a support, a casing mounted on said support, two ribs in said casing forming a guideway, jaws mounted to slide in said guideway and adapted to be held normally closed, said jaws presenting a funnel-like receiving extension with internal conical 65 walls in order that the jaws may be caused to separate to permit the insertion of a pencil when same is thrust into said funnel-like receiving extension.

8. In a device of the character described, 70 pencil holding jaws yieldingly mounted to recede from and approach each other, said jaws having complementary tapered openings therein forming a pencil receiving funnel.

9. In a device of the character described, cutting apparatus, pencil holding means comprising jaws on opposite sides of the axis of the cutting position of the pencil, said jaws being yieldingly mounted to simultaneously 80 recede from and approach said axis, each of said jaws having a tapered recess forming a pencil receiving funnel.

Signed at Chicago, Illinois, this 17th day of August, 1926.

CHARLES C. SPENGLER.
